UNITED STATES PATENT OFFICE

CHARLES H. CASTAGNE, OF CHICAGO, ILLINOIS

PARACHUTE

Application filed February 21, 1928. Serial No. 256,001.

My invention relates to parachutes in the aviation art, and more particularly to such appliances of this kind as are combined with the garment of the aviator, and my main object is to provide a novel parachute garment which has ample capacity for safely supporting the wearer during his descent.

A further object of the invention is to include in the novel garment, means for rapidly filling the garment with air to a supporting extent.

A still further object of the invention is to design the air receiving elements of the novel garment in a manner to open whether the wearer drops in upright, inverted or any other position.

Another object of the invention is to incorporate in the novel garment, a balloon extension assuring the confinement of a comparatively large amount of air for the adequate support of the wearer.

A final, but nevertheless important object of the invention is to construct the novel garment of materials readily adapted to be collapsed and compactly assembled for wear while the garment is not used as a parachute.

With the above objects in view and any others that may suggest themselves from the specification and claims to follow, a better understanding of the invention may be gained by reference to the accompanying drawings, in which—

Figure 1 is an elevation of the novel garment as in use, and partly broken away;

Fig. 2 is a medial vertical section of the lower portion of the garment as it is worn;

Fig. 3 is a similar section, taken on the line 3—3 of Figure 1; and

Fig. 4 is a rear elevation of the lower portion of the garment.

It is a familiar fact that in the aviation art great skill must be used in the handling of a parachute, the position of the same and the manner of its use being matters of imperative importance in the consideration of safety. Frequently, in spite of adherence to prescribed rules, a mishap occurs in the handling or use of the conventional parachute whereby the same fails to open or opens improperly, making a disaster unavoidable. It has been

my intention to eliminate the great danger now involved in the handling and use of present day parachutes by providing a combined garment and parachute which accomplishes the objects above outlined to the fullest extent.

Referring specifically to the drawings, 10 denotes the main portion of the garment, which is on the order of a typical jacket, suitably buttoned at 11 or otherwise secured upon the body of the wearer. The jacket 10 is extended laterally with sleeve sections 12, and upwardly with a neck section 13 which expands to form a balloon 14. While the jacket and its sleeves are made of heavy waterproof duck or other material suitable for strength, the balloon 14 is made of a special silk used for the particular purpose, and which permits the balloon to hold air when filled.

The rear of the neck portion 13 is downwardly extended along the back of the jacket in tubular form, as indicated at 15, this tubular section terminating opposite the hips of the wearer and in open form. The tubular section is extended laterally with wings 16, which are spaced backwardly from the jacket to form channels of communication with the balloon neck 13, as clearly denoted by arrows in Figure 3. The wings 16 may be suitably reinforced, join with the sleeves at 16^a, and are secured at the bottom by straps 17 wrapped around the legs of the wearer.

The balloon is formed with a flaring hood portion 18 of a circular form, which when in the shape shown in Figure 1, indicates that it is held in shape by stays 19 extended from the body of the balloon. The hood section is prevented from collapsing in an outward direction by guy cords 20 from the lower portion of the balloon.

The back of the garment is provided with a pocket 21 which is open at the top and may be further opened by a zipper-like closure 22, or other suitable means, to accommodate the collapsed balloon and hood. The drawing only shows the pocket as a matter of example, the design of the same varying with the capacity required.

When the device is not in use, the wearer

may occupy the seat of the pilot or of a passenger without undue discomfort, since the bulk of the garment will be packed in the pocket 21, but the wings 16 showing prominently. Since these wings are also of duck or other limp fabric, the wearer's arms will be free for any necessary movement; and, of course, his leg movements will not be impaired in any manner. In case it is necessary for the wearer to use the garment for parachute purposes, he need but open the pocket 21 and withdraw the balloon and hood to flow loosely behind him. He may then drop or leap into the air, in which event the latter will probably first catch the pocket presented by the hood 18. This will cause the balloon to be raised by said pocket, drawing upon the lower part of the garment in a direction to right the same and its contents. At this juncture, the air will begin to fill the balloon from the space behind the wearer, both at the center and inside of the wings 16, so that the further the descent the fuller the balloon will become of air, so that it will soon, with the cooperation of the hood 18, present a considerable resistance to the descent, and so break the fall of the subject as he approaches the ground. The above actions are readily intended to occur very rapidly, so that the garment will perform its life-saving function within a short fall. While I have experimented with the garment on a smaller scale to determine its susceptibility to conditions of the fall, it will be obvious that proportions and sizes will depend upon the actual conditions apt to be met by a garment supporting a person of average size and weight. However, the design of the novel garment is peculiar in the sense that the wearer will not be subjected to strains or painful positions on the descent. The wings 16 act as a brace to prevent the sleeves 12 from being drawn upwardly beyond the horizontal position shown, so that there will not be a tendency for the wearer's arms to be wrenched upwardly. The garment is designed to form a comfortable support for the wearer, yet to be of a character simulating a coat or jacket, which enables one to easily put it on or take it off. Further, it will be noted that the novel garment is made up of few and simple parts, and that there are not clasps or special fastening devices to be attended to. It is significant that once that garment is put on and the wearer takes his place as pilot or passenger without the apprehension of using a parachute, the present parachute is ready at a moment's notice to function in case the emergency arises. In such an event, it is not necessary for the wearer to do more than loosen the balloon and hood as previously described, and he may jump or drop from any point and in any position without fear that he will fall head-first or sidewise; as previously explained, the

novel parachute is especially designed to right itself and its charge during the early course of its descent.

I claim:—

1. An aviation garment comprising a jacket, and an inflatable bag carried by the latter and extending above the wearer of the garment and having the openings thereof disposed at the back and sides of said jacket. 70

2. An aviation garment comprising a jacket, and an inflatable bag carried by the latter extending above the same and the mouth of said bag opening downwardly at the back of said jacket. 75

3. An aviation garment comprising a jacket, and a bag carried thereby and extending above the same, said bag having an open mouth at the back of said jacket for self-inflation by movement in the air. 80

4. An aviation garment comprising a jacket, and a bag carried thereby extending above the same, said bag having an open mouth at the back and sides of said jacket for self-inflation by movement in the air, and assuming an inflated position above the jacket to support the same and the wearer in suspended position. 85

5. An aviation garment comprising a jacket, an inflatable bag attached thereto and extending above the same, and an air baffle carried by the bag adjacent the sleeves of said jacket. 90

6. An aviation garment comprising a jacket, an inflatable bag attached thereto and extending above the jacket, a skirt covering the top of the bag, and means to maintain the skirt spread from the bag to create an open pocket about the latter. 100

7. An aviation garment comprising a jacket, an inflatable bag attached thereto and extending above the jacket, a skirt extending from the bag and covering the top thereof, and stays projected from the bag to the skirt to lend the latter a spread position. 105

8. An aviation garment comprising a jacket, an inflatable bag attached thereto and extending above the jacket, a skirt extending inclinedly from the top of the bag and covering the same, and guy lines projected from points on the bag below the skirt in upward direction to the rim of the skirt to prevent the reversal of the latter. 110

9. An aviation garment comprising a jacket, an inflatable bag attached to the back thereof, and a tubular extension of the bag down the back of the jacket. 115

10. An aviation garment comprising a jacket, an inflatable bag attached to the back thereof, and a tubular extension of the bag down the back of the jacket, said extensions being open at the bottom to receive air for the inflation of the bag. 120

11. An aviation garment comprising a jacket, an inflatable bag attached to the back 125

- thereof, and baffle webs between the sides of the jacket and the sleeves thereof.
12. An aviation garment comprising a jacket, an inflatable bag attached to the back thereof, and baffle webs between the sides of the jacket and the sleeves thereof, said baffle webs receding back of the shoulder regions to meet the back wall of the bag and furnish an air inlet to the bag from the front of said webs.
13. An aviation garment comprising a jacket, an inflatable bag attached thereto and extended to meet the sleeves, and bottom braces for the latter comprising webs extended from the sides of the jacket to the sleeves.
14. An aviation garment comprising a jacket, an inflatable bag attached thereto and extended to meet the sleeves, bottom braces for the latter comprising webs extended from the sides of the jacket to the sleeves, and thigh-straps carried by the bottom sections of the webs to secure them to the wearer's body.
- 25 In testimony whereof I affix my signature.
CHARLES H. CASTAGNE.
